UNITED STATES PATENT OFFICE.

AUSTIN BOND, OF NEW YORK, N. Y.

SLICING-MACHINE.

1,273,138.

Specification of Letters Patent. Patented July 23, 1918.

Application filed February 15, 1918. Serial No. 217,313.

To all whom it may concern:

Be it known that I, AUSTIN BOND, a subject of the King of Great Britain, and residing at New York, in the county of New York and State of New York, have invented certain new and useful Improvements in Slicing-Machines, of which the following is a specification, such as will enable those skilled in the art to which it appertains to make and use the same.

This invention relates to machines for slicing meats of various kinds and classes as well as bread, cake and the like, and the object of the invention is to provide a machine of the class specified which is simple in construction and operation and efficient in use; a further object being to provide a machine of this class which may be compactly folded together for shipment or other purposes.

The invention is fully disclosed in the following specification, of which the accompanying drawings form a part, in which the separate parts of my improvement are designated by suitable reference characters in each of the views, and in which:—

Figure 1 is a plan view of my improved machine with part of the construction broken away, and indicating the parts in position for use;

Fig. 2 a sectional side view of the machine as shown in Fig. 1, the section being on the line 2—2 of said figure;

Fig. 3 a section on the line 3—3 of Fig. 1; Fig. 4 a section on the line 4—4 of Fig. 1;

Fig. 5 a partial section on the line 5—5 of Fig. 2 and on an enlarged scale; and,

Fig. 6 a partial section on the line 6—6 of Fig. 1 and on an enlarged scale.

In the drawing 10 is a main frame comprising an L-shaped base member 11, having an upright portion 12 which is approximately circular in form, and one face of the upright portion 12 is provided with a flange 13, as clearly indicated in Fig. 3, which forms an annular space 14 in the upright portion 12. The central part of the upright portion 12 is provided with an inwardly directed stud 15 on which is mounted a gear 16 to the inner face of which is secured a rotary disk knife 17.

The upright portion 12 of the frame is provided above the central portion thereof with a forwardly directed bearing 18 in which is mounted a spindle 19 to the inner end of which is secured a gear 20 which meshes with the gear 16, as clearly indi-

cated in Figs. 2 and 3, and connected with the outer end of the spindle 19 is a crank 21 provided with a handpiece 22. Secured to the top of the base member 11 of the frame, or the part 23 of said base member is a thin strip or sheet of metal 24 which extends approximately the full length of said part 23, as clearly indicated in Fig. 1, and the rear end portion of said strip is cut out as shown at 25, and inwardly of said cut out portion said strip or sheet 24 is provided with a saw-cut 26 which tapers to a point at its inner end as shown at 27, and the rotary disk knife 17 is adapted to operate in the saw-cut 26, as clearly indicated in Fig. 5, of the drawing. The saw-cut portion 26 in the strip or sheet 24 is also provided with a laterally directed recess 28 adapted to receive the end portion of a vertical member 29, which is provided at the other end with a head portion 30 through which is passed a screw 31 which threads into the stud 15 centrally of the upright portion 12 of the frame, and the member 29 is adapted to hold the gear 16 and rotary disk knife 17 in place, as will be readily understood on a consideration of Fig. 3 of the drawing.

A pickup plate 32 is secured to one side of the upright portion 12 of the frame, as clearly shown in Figs. 2 and 5, and said plate is provided with an offset portion 33, the end of which is adapted to bear on the face of the rotary disk knife 17, as clearly shown in said figure, and serves to detach the meat or other substance that might adhere to said knife in the operation of slicing the same, as will be readily understood. The plate 32 is provided with a downwardly directed flange 34 which forms a keeper for a pan or receiver box 35, which is composed of sheet metal and comprises a bottom 36, side walls 37 and a back wall 38; the keeper 34 is adapted to engage one of the side walls 37 as clearly indicated in Fig. 2, and by tilting the opposite side portion of the receiver box upwardly it may be detached from the keeper 34 and the contents collected in said box may be discharged onto a scale or the like through the open end 39 thereof, as will be readily understood.

A vertical and adjustable gage plate 40 is mounted on the front end portion of the base member 11 of the frame, as clearly indicated in Figs. 1 and 2, and a block 41 is secured to said plate, and passing through one end portion of said block is a shaft 42

which is secured in the base member 11 or the part 23 thereof in any desired manner, and a supplemental threaded shaft 43 is also secured to said part 23 of the base member 11 of the frame and ranges parallel with the shaft 42, and adjustably mounted on the outer end portion of the shaft 43 is a milled nut 44 having an inner sleeve portion 45 provided with an annular recess 46 in which 5 a part 47 of the block 41 is adapted to operate, this construction being clearly indicated in Figs. 1, 2 and 5 of the drawing, and it will be noted that the bottom portion of the gage plate 40 bears on, or passes over 10 the top of the strip or sheet 24 secured to the top of the part 23 of the base member 11 of the frame, and by adjusting the milled nut 44 on the shaft 43, the gage plate 40 may be moved horizontally into different positions 15 and the extent of such movement may be determined, or indicated by an indicator 48 secured to the shaft 42 and operating through an aperture 49 in a plate 50 secured to the top portion of the block 41 above the 20 shaft 42, said indicator being adapted to operate in connection with a scale 51 on said plate 50 as clearly indicated in Fig. 1.

The gage plate 40 extends slightly above the horizontal center line of the rotary disk 30 knife 17 and a guard device 52 is pivoted to an upwardly directed stud 53 on the top of the upright portion 12 of the frame, and a spring 54 is connected with the guard 52 and with the part 12 of the frame and serves 35 to hold said guard in a depressed position as shown in Fig. 2, and said guard extends downwardly, approximately, to the top face of the gage plate 40 and the purpose of this 40 guard device is to prevent the operator from being cut by the disk knife in the operation of the machine, as will be readily understood.

I also provide a supplemental frame 55 which is approximately rectangular in form, 45 and consists of parallel side members 56, parallel end members 57 and a central member 58 parallel with the end members 57. One of the side members 56 is provided at the ends thereof with outwardly directed 50 ears 59 through which are passed screws or similar devices 60 which pass into the ends of the part 23 of the base 11 of the frame, as clearly indicated in Fig. 5, and this construction forms a pivotal connection between 55 the main frame 10 and the supplemental frame 55. The side members 56 of the frame 55 are recessed in the top portions thereof as shown at 61, in Fig. 3, and a plate 62 is mounted on the bottom of said recess 60 and extends the full length of the frame 55 and is secured in position by screws 63 which are connected with the end members 57 of said frame as clearly indicated in Fig. 4, and the plate 62 forms a base plate or bottom 65 for the frame 55 as will be readily un-

derstood. Adjustably mounted over the plate 62 or in the side members 56 of the frame is a meat or other supporting table 64, one end of which is provided with a vertical portion 65 beaded at the top as 70 shown at 66, and mounted on the vertical portion 65 is a laterally adjustable gripping plate 67, L-shaped in form and comprising an inwardly directed portion 68, one face of which is provided with a plurality of 75 pointed members 69 and a part 70 at right angles to the part 68 and adapted to engage the vertical portion 65 of the table 64 and to slide longitudinally thereof as will be readily understood. 80

Secured to the bottom of the table 64 adjacent to the opposite sides thereof are two metal strips 71, the outer ends of which are adapted to operate in the recesses 61 in the side members 56 of the frame, as clearly 85 indicated in Figs. 1 and 3, and this construction holds the table 64 in connection with the frame 55, while permitting the sliding movement of said table over the base plate 62 connected with said frame. It will 90 be noted that the opposite sides of the table 64 overlap the side members 56 of the frame. The inner end of the table 64 is provided approximately, centrally thereof with a slot 72 which extends inwardly to the approximate 95 center of said table, or a predetermined distance from the inner end of the gripping plate 67, and adjustably mounted in said slot is a backing plate 73 which ranges vertically and which is provided with a base 100 or flange portion 74 through which is passed a headed bolt having a winged nut 75, whereby said backing plate may be located in any position of adjustment on the plate 64, and a guide pin 76 is also passed through the flange 74 and through the slot 72 and serves to hold the backing plate 73 against swinging movement. 105

A strip 77 of metal is secured to the bottom of the table 64 and ranges diagonally 110 thereof, and is adapted to operate as a stop device to limit the forward and backward movement of said table over the base plate 62, the strip 77 operating in connection with the heads of the screws 63, as clearly indicated in Figs. 1, and 4 of the drawing. 115

The main frame 10, or the base 11 thereof, is of greater vertical dimensions than the supplemental frame 55, and pivoted to the outer side 56 of the supplemental frame 120 approximately centrally thereof is a foot piece and lock device 78, comprising a U-shaped portion 79 which when in the position shown in Figs. 3 and 4 ranges vertically and operates as a foot piece for the frame, said device being provided with a hook-shaped portion 80 which ranges at an angle to the U-shaped portion 79 and which is adapted to engage the stud 53 on the top of the upright portion 12 of the frame when the 125 130

supplemental frame 55 is swung vertically on its pivotal connection with the main frame 10, and will serve to hold said main and supplemental frames together in their 5 folded position.

It will be understood that in folding the supplemental frame 55 the backing plate 73 will be detached from the table 64 and the gripping plate 67 will be moved outwardly 10 far enough to clear the top of the gage plate 40, as will be readily understood, and by detaching the pan or receiver box 35 and crank 21, my improved machine and the various parts connected therewith may be 15 compactly wrapped together for shipping or other purposes as will be readily understood.

From the foregoing description the operation of my improved machine will be 20 readily understood when taken in connection with the accompanying drawings and the following statement. The position of the parts shown in the drawings are their normal or operative position, and when it is 25 desired to slice a piece of meat for example, the same is placed upon the table 64 and the gripping plate moved inwardly to force said meat against the gage plate 40, after which the backing plate 73 is moved forwardly 30 into engagement with the rear end portion of the meat, it being understood that the gage plate 40 has been adjusted to determine the desired thickness of the slice to be 35 cut from said meat, after which the crank 21 is operated to rotate the rotary disk knife 17 in which operation the left hand of the operator grasps the gripping plate 67 and the vertical portion 65 of the table 64, and the meat supported on said table between 40 the gripping plate and the gage plate 40 is moved backwardly by hand, or by sliding said table 64 backwardly over the base plate 62 of the frame, as will be readily understood, in which operation the backing plate 45 73 operates to prevent the slipping of the meat off from the table 64 both in the forward as well as the backward movement of said table. The rotation of the rotary knife 17 in the saw-cut 26 in the sheet or strip 24 50 forms a scissor cut for the meat, or the like, between said knife and the plate 24, as will be readily understood, and in this way or by means of this construction a perfectly clean cut is obtained.

Having fully described my invention, what I claim as new and desire to secure by Letters Patent, is:—

1. In a machine of the class described, a frame, comprising a base portion and an 60 upright portion, a plate secured to the top of the base portion and provided at one end thereof with a beveled saw-cut, a rotary knife mounted in the upright portion of said frame and adapted to operate in said 65 saw-cut, and means mounted in said upright

portion of the frame for operating said rotary knife.

2. In a machine of the class described, a frame, comprising a base portion and an upright portion, a plate secured to the top 70 of the base portion and provided at one end thereof with a beveled saw-cut, a rotary knife mounted in the upright portion of said frame and adapted to operate in said saw-cut, means mounted in said upright portion 75 of the frame for operating said rotary knife, and a gage device adjustably mounted in connection with the base portion of said frame.

3. In a machine of the class described, a 80 frame, comprising a base portion and an upright portion, a plate secured to the top of the base portion and provided at one end thereof with a beveled saw-cut, a rotary knife mounted in the upright portion of said 85 frame and adapted to operate in said saw-cut, means mounted in said upright portion of the frame for operating said rotary knife, a gage device adjustably mounted in connection with the base portion of said frame, 90 and a pickup plate secured to the upright portion of the frame and operating in connection with one face of the rotary knife.

4. In a machine of the class described, a 95 frame, comprising a base portion and an upright portion, a plate secured to the top of the base portion and provided at one end thereof with a beveled saw-cut, a rotary knife mounted in the upright portion of said frame and adapted to operate in said saw-cut, means mounted in said upright portion 100 of the frame for operating said rotary knife, a gage device adjustably mounted in connection with the base portion of said frame, a pick up plate secured to the upright portion 105 of the frame and operating in connection with one face of the rotary knife, and a tensionally controlled guard device pivoted to the upright portion of said frame.

5. In a machine of the class described, a 110 main frame, comprising a base portion and an upright portion, a plate secured to the top of the base portion and provided at one end thereof with a beveled saw-cut, a rotary knife mounted in the upright portion 115 of said frame and adapted to operate in said saw-cut, means mounted in said upright portion of the frame for operating said rotary knife, a gage device adjustably mounted in connection with the base portion of said frame, a pickup plate secured to the upright portion of the frame and operating in connection with one face of the 120 rotary knife, a tensionally controlled guard device pivoted to the upright portion of said frame, a supplemental frame pivoted to the main frame and a table movable longitudinally of said supplemental frame.

6. In a machine of the class described, a 125 main frame, comprising a base portion and 130

- an upright portion, a plate secured to the top of the base portion and provided at one end thereof with a beveled saw-cut, a rotary knife mounted in the upright portion 5 of said frame and adapted to operate in said saw-cut, means mounted in said upright portion of the frame for operating said rotary knife, a gage device adjustably mounted in connection with the base portion 10 of said frame, a pickup plate secured to the upright portion of the frame and operating in connection with one face of the rotary knife, a tensionally controlled guard device pivoted to the main frame, a table movable longitudinally of said supplemental frame, and a gripping plate movable transversely of said table. 15
7. In a machine of the class described, a main frame, comprising a base portion and 20 an upright portion, a plate secured to the top of the base portion and provided at one end thereof with a beveled saw-cut, a rotary knife mounted in the upright portion of said frame and adapted to operate 25 in said saw-cut, means mounted in said upright portion of the frame for operating said rotary knife, a gage device adjustably mounted in connection with the base portion of said frame, a pick-up plate secured 30 to the upright portion of the frame and operating in connection with one face of the rotary knife, a tensionally controlled guard device pivoted to the main frame, a table movable longitudinally of said supplemental frame, a gripping plate movable transversely of said table, and a backing plate adjustable longitudinally of said table. 35
8. In a machine of the class described, a main frame, a rotary knife mounted in said 40 frame, a gage device adjustably mounted on said frame, a supplemental frame pivoted to the main frame and the opposite sides of which are provided with recesses, a table mounted on said supplemental frame and 45 provided with parts adapted to enter the recesses in the sides of said supplemental frame to permit the movement of said table longitudinally of said frame, and means for limiting the extent of such movement. 50
9. In a machine of the class described, a main frame, a rotary knife mounted in said frame, a gage device adjustably mounted on said frame, a supplemental frame pivoted to the main frame and the opposite sides 55 of which are provided with recesses, a table mounted on said supplemental frame and provided with parts adapted to enter the recesses in the sides of said supplemental frame to permit the movement of said table longitudinally of said frame, means for 60 limiting the extent of such movement, and a gripping plate movable transversely of said table. 65
10. In a machine of the class described, a main frame, a rotary knife mounted in said frame, a gage device adjustably mounted on said frame, a supplemental frame pivoted to the main frame and the opposite sides of which are provided with recesses, a table mounted on said supplemental frame and provided with parts adapted to enter the recesses in the sides of said supplemental frame to permit the movement of said table longitudinally of said frame, means for 70 limiting the extent of such movement, a gripping plate movable transversely of said table one end portion of said table being slotted and a backing plate adjustable longitudinally of said table and in operative connection with said slot. 75
11. In a machine of the class described, a main frame, a rotary knife mounted therein, a gage device adjustably mounted in said main frame, a supplemental frame pivoted to the main frame, a table movable longitudinally of the supplemental frame and a gripping plate mounted to move transversely of said table. 80
12. In a machine of the class described, a main frame, a rotary knife mounted therein, a gage device adjustably mounted on said main frame, a supplemental frame pivoted to the main frame, a table movable longitudinally of the supplemental frame, a gripping plate mounted to move transversely of one end portion of said table and a backing plate adjustable longitudinally of the other end portion of said table. 85
13. In a machine of the class described, a main frame, a rotary knife mounted therein, a gage device adjustably mounted on said main frame, a supplemental frame pivoted to the main frame, a table movable longitudinally of the supplemental frame, a gripping plate movably mounted on said table, a pickup device secured to the main frame and operating in connection with one face of the rotary knife, and a pan or receiver box detachably connected with the main frame. 90
- In testimony that I claim the foregoing as my invention I have signed my name, in presence of the subscribing witnesses, this 14th day of February, 1918.
